UNITED STATES PATENT OFFICE.

PHILIP A. MYERS, OF ASHLAND, OHIO, ASSIGNOR TO F. E. MYERS AND BROTHER, A COPARTNERSHIP CONSISTING OF FRANCIS E. MYERS AND PHILIP A. MYERS, OF ASHLAND, OHIO.

WORKING HEAD FOR PUMPS.

1,170,662.

Specification of Letters Patent.

Patented Feb. 8, 1916.

Application filed July 22, 1914. Serial No. 852,508.

To all whom it may concern:

Be it known that I, PHILIP A. MYERS, a citizen of the United States, residing at Ashland, in the county of Ashland and State of Ohio, have invented certain new and useful Improvements in Working Heads for Pumps, of which the following is a specification, reference being had therein to the accompanying drawing.

10 This invention relates to working heads for pumps, and more particularly to the frame or structure which supports the pump and its operating mechanism.

15 The object of the invention is to provide a structure of this kind which can be used with pumping devices of different kinds and of various sizes; and to make the side members of the frame interchangeable.

20 A further object is to provide a frame of this character which, when assembled, will "square itself up," and which will form a very rigid construction when assembled with any of the pumps with which it can be used.

25 A further object of the invention is to provide, in combination with a frame of this kind, a combined water and air pumping mechanism.

30 In the accompanying drawings Figure 1 is a front elevation partly in section of a working head embodying my invention, and having mounted thereon a combined air and water pumping mechanism; Fig. 2 is a vertical section taken on the line $x-x$ of Fig.

35 Fig. 1, looking in the direction of the arrows; Fig. 3 is a transverse sectional view taken on the line $y-y$ of Fig. 1; Fig. 4 is a front elevation of a working head, showing the frame arranged to receive a double acting

40 pump cylinder which is mounted directly on the frame; Fig. 5 is a front elevation of a working head showing the same supporting a submerged pumping mechanism; Fig. 6 is a vertical sectional view of a working head mounted upon a sub-base; Fig. 7

45 is a side elevation of the same; and Fig. 8 is a side elevation of a working head embodying the invention and comprising a sub-base of a different kind.

50 In these several drawings I have illustrated a single embodiment of my invention and have shown it arranged for use in connection with pumping devices of various kinds. It will be understood, however,

55 that the frame construction here shown is

chosen for the purpose of illustration only and, further, that the pumping devices shown in the several figures are chosen as illustrative of the various uses to which the frame may be put. In each of these figures 60 the frame comprises two units or side members which are, preferably, exactly alike and are connected one with the other by detachable connecting members. Each of these frame members comprises a base 1 65 adapted to support pump operating mechanism, and having rigidly secured thereto and extending upwardly therefrom, guide rods 2 and brace rods 3, these rods being rigidly connected one to the other at their 70 upper ends, preferably by a head block 4. The guide rods 2 are preferably vertical, while the brace rods 3 extend at an inclination to the plane of the guide rods, this arrangement being permitted by the difference in the widths of the base 1 and the head block 4. These rods may be connected with the base and the head block in any suitable manner. In the present instance the rods are cast in the base and head block 75 so that each frame member constitutes a unitary structure and is completely formed in the foundry. The two side members of the frame being exactly alike, a single pattern 80 will answer for all the castings, and any two frame members can be assembled to make a frame without regard to whether they go on the right or the left hand side. The two frame members which make up the 85 frame are here shown as connected together by tie rods 5 and 6 which extend through apertures in the base and the head block respectively, and are rigidly connected to these parts by means of set screws 7 and 8. Obviously, by adjusting the frames along the tie rods, or by substituting tie rods of different lengths, the distance between the frame members, and consequently the width 90 of the frame, may be varied.

95 The pumping devices are supported by the guide rods 2 and where the pumping devices comprise a reciprocating piston the cross head which operates this piston is slidably mounted on the guide rods 2, the length of the guide rods being such as to allow ample space for the reciprocation of the cross head between the tops of the pumping devices and the head blocks. The manner of connecting the pumping devices to the frame members depends upon the na- 100 105 110

ture of the pumping devices themselves. In Fig. 1 I have shown a device adapted for connection with a submerged pump, and have provided this device with a water-cooled air pumping cylinder coöperating with the water pumping mechanism.

The water pumping devices comprise a submerged cylinder of a well known type such as is shown at 9, which is connected by 13 a pipe 10 with the lower end of a cylinder or discharge head 11, which is secured to the side members of the frame. Preferably the cylinder is provided at its opposite sides with brackets or clamping devices as shown 15 at 12, these clamping devices being preferably formed of separable parts as shown in Fig. 3, so that the cylinder can be very quickly and easily attached to the vertical rods of the frame. A pumping rod 13 extends from the cylinder of the pumping device 9 upward through to the pipe 10, and through the discharge head 11, and is connected at a point above the discharge head with a cross head 14, provided at its opposite 20 ends with vertical bearings to receive the guide rods 2 and slidably support the cross head on these rods. The cross head is here shown as divided longitudinally on a vertical line to form two parts, the line of 25 division being through the bearings for the rods and the socket for the upper end of the pumping rod. The two parts of the cross head are connected one to the other by bolts 15. This construction enables the cross head 30 to be very quickly and easily attached to the guide rods and the pumping rod, and when so attached forms a very strong durable construction. The cross head is preferably provided at its outer ends with pintles 35 on which are journaled the upper ends of connecting rods 17, the lower ends of which are mounted on wrist pins 18, carried by crank wheels 19. The crank wheels 19 are preferably in the form of gears which are 40 mounted on a shaft 20 journaled in bearings 21 formed in the bases of the two side members of the frame. The gears 19 mesh with pinions 22 secured to a shaft 23 journaled in bearings 24 also formed in the base castings 1 of the frame members. The shaft 23 constitutes the driving shaft and may be connected with the source of power in any suitable manner. In the present instance it is shown as provided with a belt wheel 25. 50 The water is discharged from the forward side of the discharge head 11, through a suitable discharge opening, which is not here shown. Pumps of this type are frequently used in connection with storage tanks which utilize compressed air to force the water through the distributing pipes, and consequently, it is desirable that they should be provided with air pumping devices to enable a proper quantity of air to 60 be forced into the tanks. Some difficulty is 65

experienced in preventing these air pumping devices from overheating, and, in the present construction, I have provided an air pumping cylinder which is so arranged as to be operated from the cross head 14, and 70 as to be constantly surrounded by water, which will prevent the same from becoming overheated. To this end the discharge head 11 is provided with a laterally extending portion 26 in which is mounted an air pumping cylinder 27 of an exterior diameter somewhat less than the interior diameter of the part 26 of the head. The cylinder 27 is mounted at its upper and lower ends in the upper and lower ends respectively of 75 the discharge head, and is provided with valve controlled inlet and discharge ports 28 and 29 which communicate respectively with the atmosphere and with the discharge head. A piston 30 is mounted in the cylinder 27 and connected by means of a rod 31 with the cross head 13. The connection between the rod and the cross head is preferably formed by means of a pin 32, the removal of which will disconnect the piston 30 80 from the cross head, and consequently render the air pumping apparatus inoperative. The air pumping apparatus being constantly surrounded by the water within the head 11, it will be apparent it will not become 85 heated.

In Fig. 4 of the drawings I have illustrated the frame as assembled with a double acting pump, the pumping cylinder 33 being mounted directly upon the guide rods 2 by means of clamping brackets 34. This cylinder has its piston 35 connected with the cross head 14 by a piston rod 36, and has at its lower end a screw-threaded boss or tap 37 to receive the suction pipe.

In Fig. 5 of the drawings I have shown the frame as supporting a submerged pump. As here shown a supporting bar 40 is clamped to the rods 2 of the frame and supports pipes 41, which in turn support a 11 pumping cylinder 42.

In the several forms of the device heretofore described, the bases or feet, as they might be called, of the side frames are shown as forming the base of the working head, that is, they are the parts which are secured to the platform. However, it is not necessary to an embodiment of the invention that these should constitute the supporting base. It is possible, and under some circumstances might be preferable, to form a separate supporting base and mount the bases of the side frames on the supporting bases. Such a construction is shown in Figs. 6 and 7 of the drawings. Here the construction of the side members is similar to that heretofore shown, but the bases of the two side members are mounted upon a sub-base 45, which sub-base is adapted to be mounted upon the platform or other supporting surface. When a sub- 12

base or similar device is used in connection with the side frames, it is not necessary that the lower tie rod 5 should be employed, because the side members are rigidly secured to the sub-base by bolting, or otherwise, and this serves to space the side frame members apart and thus the sub-base constitutes the connecting means between the two side members. When it is desired to vary the distance between the side frame members to accommodate pumping devices of different kinds, this may be done either by providing a special base of a different width or by changing the position of the bolt holes in the sub-base. As shown in this form of the device the working head is provided with a submerged pumping device, the cylinder of which is shown at 48 and is connected, by a connecting pipe 49, with a discharge head 50 which is clamped on to the guide rods 2 in the manner above described. The piston rod for the pumping device, which is shown at 51, extends through the connecting pipe and the discharge head, and is operated in the same manner as the piston rod shown in Fig. 1. In either instance the result is the same.

In Fig. 8 is shown a further example of the side frame members mounted upon a supporting base. In this construction the sub-base is of such a character that the pumping devices can be withdrawn without disturbing the base or the discharge line. Such a base is shown generally at 46 in Fig. 8, and the mechanism is fully shown and described in my Patent No. 928,234, of July 13, 1909. To accommodate the side members to this frame the bases of the two side members, which are indicated at 47, are slightly different in shape from those shown in the other drawings, but the guide rods 2 and brace rods 3 are arranged in a similar manner.

I have shown one embodiment of my invention, with slight modifications, and have shown the same as used in connection with several different kinds of pumping devices, but it will be understood that the side frame members themselves may be modified in form, and that they may be used in connection with pumping devices of various kinds, either with or without a sub-base or supplemental supporting device. For example, while I prefer to cast one or both of the rods of each frame member in the base and the head, this is not essential, as a rigid construction might be secured in other ways. Further, the character and arrangement of these rods may be varied according to the demands of the particular pumping device with which the invention is employed. In some instances the vertical rods may not constitute guide rods, or the rods may not be arranged vertically, or the brace rod may be omitted and bracing action secured in some

other manner. Therefore, I do not wish to be limited to the details shown and described for obvious modifications will occur to one skilled in the art.

Having thus fully described my invention, what I claim as new and desire to secure by Letters Patent, is:—

1. A supporting frame for a pump comprising a plurality of separate units arranged side by side and spaced apart to receive pumping mechanism between them, and connecting devices to rigidly connect said units one to the other and to maintain the same in their spaced relation, said connecting devices being detachably secured to said units to permit said units to be separated and their relative positions altered.

2. A supporting frame for a pump comprising a plurality of separate units arranged side by side and spaced apart to receive pumping mechanism between them, each of said units comprising a base, a guide rod and a brace rod rigidly secured at their lower ends to said base, and a head block rigidly secured to and connecting together the upper ends of said guide rod and said brace rod, and connecting devices extending between and detachably secured to the bases and the head blocks, respectively, of said units to rigidly connect said units to form a unitary structure.

3. A supporting frame for a pump comprising a plurality of separate units arranged side by side and spaced apart to receive pumping mechanism between them, said units being interchangeable, and connecting devices to rigidly connect said units one to the other and maintain them in their proper relative positions, said connecting devices being adapted to be secured to either side of any one of said units, whereby said units may be connected one to the other in different relative positions.

4. A supporting frame for a pump comprising a plurality of separate units arranged side by side and spaced apart to receive pumping mechanism between them, said units being interchangeable and each comprising a base, a guide rod and a brace rod rigidly secured at their lower ends to said base, and a head block, rigidly secured to the upper ends of said rods, the base and head block of each unit having sockets opening on either side thereof, tie rods adapted to enter the sockets on either side of any one of said units, and means for detachably securing said tie rods in the sockets.

5. A supporting frame for a pump comprising a plurality of separate units arranged side by side and spaced apart to receive pumping mechanism between them, each of said units comprising a base and a guide rod rigidly secured to said base, connecting devices to rigidly connect said units one to the other and maintain them in their

proper relative positions, said connecting devices being detachable to permit said units to be separated and their relative positions altered, and a pumping device detachably secured to the guide rods of the respective units.

6. A supporting frame for a pump comprising a plurality of separate units arranged side by side and spaced apart to receive pumping mechanism between them, each of said units comprising a base and a guide rod rigidly secured to said base, connecting devices to rigidly connect said units one to the other and maintain them in their proper relative positions, said connecting devices being detachable to permit said units to be separated and their relative positions altered, a pumping device detachably secured to the guide rods of the respective units, and an operating device detachably and slidably mounted on said guide rods above said pumping device and operatively connected with said pumping device.

7. A supporting frame for a pump comprising a plurality of units arranged side by side and spaced apart to receive pumping mechanism between them, each of said units comprising a base having an aperture therethrough adapted to receive a tie rod in either end thereof, a guide rod and a brace rod having their lower ends cast into said base and a head block having an aperture therethrough adapted to receive a tie rod in either end thereof, tie rods adapted to enter said apertures, and means to detachably secure said tie rods in said apertures, whereby said units are rigidly connected one to the other.

8. A supporting frame for a pump comprising a plurality of separate units ar-

ranged side by side and spaced apart to receive pumping mechanism between them, each of said units comprising a base and a guide rod rigidly secured to said base, connecting devices to rigidly connect said units one to the other and maintain them in their proper relative positions, said connecting devices being detachable to permit said units to be separated and their relative positions altered, a discharge head arranged between said discharge head and detachably secured to said guide rods, a pumping device supported by said discharge head and communicating therewith, an air pumping cylinder mounted within said discharge head and spaced away from the walls thereof, a piston mounted in said air pumping cylinder, a cross head detachably and slidably mounted on said guide rods above said discharge head, and an operative connection between said cross head and said pumping device and the piston of said air cylinder.

9. The combination with a frame, a discharge head mounted on said frame, a pumping device connected with said discharge head and means for operating said pumping device, of an air pumping cylinder mounted within said discharge head and spaced away from the walls thereof, a piston mounted in said air cylinder and a detachable connection between said piston and the operating means for said pumping device.

In testimony whereof, I affix my signature in presence of two witnesses.

PHILIP A. MYERS.
